UNITED STATES PATENT OFFICE.

MAX SCHEUER AND RALPH SCHEUER, OF NEW YORK, N. Y., EXECUTORS
OF SIMON SCHEUER, DECEASED.

FRAME FOR POCKET-BOOKS, PURSES, OR SATCHELS.

SPECIFICATION forming part of Letters Patent No. 527,512, dated October 16, 1894.

Application filed August 4, 1894. Serial No. 519,433. (No model.)

To all whom it may concern:

Be it known that SIMON SCHEUER, deceased, late of New York city, New York, (and of whose estate MAX SCHEUER and RALPH SCHEUER, of New York city, aforesaid, are executors,) has invented an Improved Frame for Pocket-Books, Purses, or Satchels, of which the following is a specification.

This invention relates to a frame for pocket books, purses and satchels which is slotted sidewise for the passage and play of a laterally extending knob secured to a spring arm which is riveted to said frame. This laterally extending knob or handle, owing to its protected position will not be apt to become accidentally opened by a pressure upon the top of the frame.

In the accompanying drawings: Figure 1 is a side elevation, partly in section, of the improved frame. Fig. 2, is a cross section, on line 2, 2, Fig. 1, showing the catch closed. Fig. 3 is a similar section showing the catch open. Fig. 4 is a longitudinal section on line 4, 4, Fig. 1. Fig. 5 is a side elevation of a modification of the frame. Fig. 6 is a cross section on line 6, 6, Fig. 5, showing the catch closed. Fig. 7 is a similar section showing the catch open, and Fig. 8 is a longitudinal section on line 8, 8, Fig. 5.

The letters a , a' , represent the two jaws of a frame for pocket books, purses, satchels or similar articles. They are connected at their ends by pivots a^2 , and are L shaped in cross-section as usual. To the lower side of jaw a , there is riveted at b' , a longitudinally extending spring arm b . This arm has an inwardly extending lateral hook b^2 , and an outwardly

extending lateral handle or knob b^3 . The hook b^2 , is adapted to enter beneath the jaw a' , when the frame is closed, and to engage a catch c , secured to said frame. The handle b^3 , projects sidewise through a slot or opening a^3 , which is formed in the side or upright portion of jaw a . To operate the catch, it is only necessary to depress handle b^3 and disengage the hook b^2 , so as to release jaw a' .

It will be seen that in this improved frame, the handle b^3 , projects to the side of the pocket book, and is not apt to be accidentally opened.

In Figs. 5 to 8, the construction is the same as above described, the only difference being that the catch is opened by raising, instead of by lowering the knob or handle b^3 . In this modification, the hook b^2 , engages the upper edge of catch c , and not the lower edge, as in Figs. 1 to 4.

What is claimed is—

The combination of pivotally connected L shaped jaws a' , a , of which jaw a' , has a catch and jaw a , has a notched upright side, with a spring arm secured within jaw a , and having a keeper and a handle that project laterally in opposite directions, all being so constructed that the keeper is adapted to enter jaw a' , and engage the catch, while the handle is adapted to pass in an opposite direction through the notched upright side of jaw a , substantially as specified.

MAX SCHEUER,
RALPH SCHEUER,
Executors of Simon Scheuer, deceased.
